Joseph M. Chiascione, Miami, Fla.

Application April 17, 1957, Serial No. 45,771

Term of patent 14 years

(Cl. D81—10)

FIG. 1

FIG. 2

FIG. 3

FIG. 4

FIG. 5

Figure 1 shows my combined portable stove and griddle in perspective and as viewed from the front.

Figure 2 is a view similar to Figure 1 with the griddle element in an adjusted position.

Figure 3 is a plan view of my combined portable stove and griddle with the griddle element moved partly to one side, as in Figure 2, and with the drawer partly opened.

Figures 4 and 5 show my combined portable stove and griddle in rear and right hand side elevation, respectively.

I claim:

The ornamental design for a combined portable stove and griddle, as shown and described.
